UNITED STATES PATENT OFFICE

2,332,566

LIGHTER

Irving Florman, New York, N. Y.

Application February 19, 1942, Serial No. 431,572

10 Claims. (Cl. 67—4.1)

This invention relates to lighters and especially to table lighters of the pyrophoric type.

The primary object of the invention is to provide a lighter of this type which is convenient and easy to operate, and which is fully effective.

In the past, most types of table lighters, that is lighters formed in two parts consisting of a base and a torch member removably mounted in the base, have operated through some cooperation between the base and the torch mount. In other words, either the lighter was operated during removal of the torch, which required a heavy base, or the holding of the base with one hand; or the lighter after removal from the base has required some sort of contact with a cooperating part on the base to cause it to ignite. The primary object of the present invention is to provide a base type lighter in which the torch member is operative when removed from the base without any cooperation with the base, and entirely independently thereof; although the torch may be extinguished by returning it to its position in the base.

A further object of the invention is to provide a torch type of mechanism in which the lighter body is held between the second and third fingers and the lighting is caused by pressure of the thumb. More particularly, the invention contemplates a lighter construction having an elongated body adapted to be engaged between the second and third fingers and provided with a flange forming an abutment for engagement by these fingers, with a button on the opposite side of the flange engageable by the thumb and connected to the lighting mechanism so as to operate the lighter when depressed.

Still another object of the invention is to provide in a lighter of this kind a snap action mechanism controlled by the thumb button which creates a strong spark capable of igniting the wick. More especially, the invention contemplates a pawl connection between the button and the sparking wheel, with a special construction for maintaining the pawl in proper position after each operation.

Further objects and advantages of the invention will appear more fully from the following description, particularly when taken in conjunction with the accompanying drawings which form a part thereof.

In the drawings:

Fig. 1 shows in side elevation, with parts broken away, a lighter embodying my invention.

Fig. 2 shows in side elevation the torch member in operated position.

Fig. 3 is a rear elevation of the lighting mechanism of the torch member.

Figs. 4 and 5 are cross-sections on the lines 4—4 and 5—5 respectively of Fig. 3; and

Fig. 6 is a cross-section on the line 6—6 of Fig. 4.

The base of the lighter may be of any suitable size and shape, and is shown in the drawings, as an ornamental glass bottle 2 having a metal cap 4. This cap is provided with a central opening forming an entrance to a metal tube 6 which extends inwardly into the base 2. It should be understood however that any type of base having an opening into a chamber or well therein would come within the contemplation of the invention.

The torch member has a body composed of a tube 8 closed by a wall 10 at one end. The other end is provided with an external thread 12. In the neighborhood of, but spaced from this second end is a transverse plate member 14. This plate member however does not entirely enclose the casing, but provides an abutment for retaining the cotton wadding 16 for holding fuel. Fuel may be supplied to the wadding by pouring it into the end of the casing 8 past the wall 14.

Mounted on the closed end 10 of the casing is a plate 18 having upstanding ears 20. Extending through both the plate 18 and the top wall 10 is a wick tube 22 in which is mounted a suitable wick 24 which extends downwardly into the cotton 16 to receive fuel therefrom. Likewise extending through plate 18 and wall 10, and at its other end through wall 14, is a flint tube 26 closed at its inner end by a threaded plug 28 and containing a coil spring 30 pressing outwardly a flint 32. Flint 32 engages the surface of a flint wheel 34 rotatably mounted on a shaft 36 in the ears 20.

Likewise pivoted on shaft 36 is a U-shaped operating member having legs 38 and 40 journaled on the shaft 36 and a connecting wall 42 on the opposite side from the wick 24. Leg 38 has a projecting pawl member 44 engageable with teeth 46 in the adjacent face of the flint wheel 34, so that when the leg 38 is turned in one direction (clockwise in Fig. 4) it will rotate the flint wheel, while it will move freely over the flint wheel when turned in the opposite direction.

Between the leg 40 and the other end of the flint wheel 34 is a coil spring 48 having one end 50 engaged against the ear 20, and the other end 52 engaged over the top of the wall 42. This spring tends to turn the U-shaped member clockwise in Fig. 4, in a direction to turn wheel 34 and thus throw sparks from flint 32 onto wick 24.

Slidably mounted in a tube 54 in the top wall 10

and plate 18, and also in the wall 14, is a rod 56. At the end opposite the lighting mechanism this rod carries an inwardly extending arm 58 provided with a centering pin 60. A coil spring 62 engaged between arm 58 and plate 14 urges rod 56 away from the lighting mechanism (downwardly in Fig. 4). Centering pin 60 engages in a conical base portion 64 of a pin or button 66 slidable in a closure 68 which is threaded on the thread 12 and thus closes the body 8. At its upper end in Fig. 4, rod 56 has a slot in which is mounted on a pivot 70 a pawl member having a portion 72 located below a notch 74 in the back wall 42 of the U-shaped member and an opposite portion 76 engageable with the flanged upper end 78 of the tube 54.

The mechanism thus described operates as follows:

When the torch is within the base in the position shown in Fig. 1, it is removed by sliding the first and second fingers beneath the flange 69 first and as the button 66 is advanced the U-shaped member is turned counter-clockwise in Fig. 4 through approximately 75°. Eventually, in its turning motion, the back wall 42 moves to the left in Fig. 4 sufficiently to disengage itself from the pawl end 72. Spring 68 then rotates the U-shaped member rapidly in a clockwise direction. Pawl 44 engaging teeth 46 turns flint wheel 34 with the U-shaped member and throws a spark from the flint onto the wick, thus igniting the wick.

When the pressure of the thumb is released, pawl end 72 engages the upper edge of wall 42 and is tilted enough (clockwise in Fig. 4) to slide down past the wall to its normal position as the rod 56 returns under the action of spring 62. However, when the rod 56 reaches its lowermost position, the pawl portion 76 engages flange 78 of tube 54 and turns end 72 back to a position beneath the notch 74. The parts are thus restored to their starting position, but the torch remains lit although the thumb is not maintained on the button 66.

To extinguish the torch, it is only necessary to restore it to the base 2, from which it can readily be removed for a further operation.

While I have described herein some embodiments of my invention, I wish it to be understood that I do not intend to limit myself thereby, except within the scope of the appended claims.

I claim:

1. A lighter comprising an elongated casing having a fuel reservoir therein and having a lighting end and a handle end, said casing having a portion adjacent the handle end of a size to be grasped between two adjacent fingers and an enlarged part between such portion and the handle end to form an abutment for the fingers, a wick extending from within the fuel reservoir through the lighting end, a flint wheel rotatably mounted on the lighting end, means to hold a flint against said wheel, a rod slidably mounted in the casing and extending longitudinally thereof, said rod projecting beyond the lighting end of the casing, a member pivoted to turn on the same axis as said flint wheel, a one-way connection between said member and said flint wheel whereby when said member moves in one direction it turns said flint wheel to ignite the wick, a spring tending to move the member in such direction, a pawl

carried by said rod engageable with the member to move it in the opposite direction against the action of the spring when the rod is pushed outwardly from the lighting end, said pawl on continued movement moving apart from the member to release the same so that said spring moves the member and turns the flint wheel to ignite the wick, a second spring acting on said rod to return the same into the casing, said pawl in such return movement engaging said member and being tilted aside thereby, means engageable with said pawl after it passes the member in such return movement to tilt it to a position to engage said member on the next operating movement of the rod, and means at the handle end of the casing engageable by the thumb when two adjacent fingers grip such portion to move the rod.

2. A lighter comprising an elongated casing having a fuel reservoir therein and having a lighting end and a handle end, said casing having a portion adjacent the handle end of a size to be grasped between two adjacent fingers and an enlarged part between such portion and the handle end to form an abutment for the fingers, a wick extending from within the fuel reservoir through the lighting end, a flint wheel rotatably mounted on the lighting end, means to hold a flint against said wheel, a rod slidably mounted in the casing and extending longitudinally thereof, said rod projecting beyond the lighting end of the casing, a member pivoted to turn on the same axis as said flint wheel, whereby when said member moves in one direction it turns said flint wheel to ignite the wick, a spring tending to move the member in such direction, a pawl carried by said rod engageable with the member to move it in the opposite direction against the action of the spring when the rod is pushed outwardly from the lighting end, said pawl on continued movement moving apart from the member to release the same so that said spring moves the member and turns the flint wheel to ignite the wick, a second spring acting on said rod to return the same into the casing, said pawl in such return movement engaging said member and being tilted aside thereby, means engageable with said pawl after it passes the member in such return movement to tilt it to a position to engage said member on the next operating movement of the rod, a button slidably mounted in the handle end of the casing engageable by the thumb when two adjacent fingers grip such portion, and means operatively connecting said button to said rod.

3. A lighter comprising an elongated casing having a fuel reservoir therein and having a lighting end and a handle end, said casing having a portion adjacent the handle end of a size to be grasped between two adjacent fingers and an enlarged part between such portion and the handle end to form an abutment for the fingers, a wick extending from within the fuel reservoir through the lighting end, a flint wheel rotatably mounted on the lighting end, means to hold a flint against said wheel, a rod slidably mounted in the casing and extending longitudinally thereof, said rod projecting beyond the lighting end of the casing, a member pivoted to turn on the same axis as said flint wheel, a one-way connection between said member and the flint wheel, whereby when said member moves in one direction it turns said flint wheel to ignite the wick, a spring tending to move the member in such direction, a pawl pivoted on said rod outside said lighting end having a section engageable with the member to move it in the opposite direction against the ac-

tion of the spring when the rod is pushed outwardly from the lighting end, said section on continued movement of the rod moving apart from the member to release the same so that said spring moves the member and turns the flint wheel to ignite the wick, a second spring acting on said rod to return the same into the casing, said pawl section in such return movement engaging said member and being tilted aside thereby, said pawl having a second section engageable with the lighting end after the first section passes the member in its return movement to tilt the first section to a position to engage said member on the next operating movement of the rod, and means at the handle end of the casing engageable by the thumb when two adjacent fingers grip such portion to move the rod.

4. In a lighter, a casing having a lighting end and a fuel reservoir therein, a wick extending from within the fuel reservoir through the lighting end, a flint wheel rotatably mounted on the lighting end, means to hold a flint against said wheel, a rod slidably mounted in the casing and extending longitudinally thereof, said rod projecting beyond the lighting end of the casing, a movable member on the lighting end, a one-way connection between said member and the flint wheel whereby when said member moves in one direction it turns said flint wheel to ignite the wick, a spring tending to move the member in such direction, a pawl carried by said rod engageable with the member to move it in the opposite direction against the action of the spring when the rod is pushed outwardly from the lighting end, said pawl on continued movement moving apart from the member to release the same so that said spring moves the member and turns the flint wheel to ignite the wick, and means to move the rod.

5. In a lighter, a casing having a lighting end and a fuel reservoir therein, a wick extending from within the fuel reservoir through the lighting end, a flint wheel rotatably mounted on the lighting end, means to hold a flint against said wheel, a rod slidably mounted in the casing and extending longitudinally thereof, said rod projecting beyond the lighting end of the casing, a member pivoted to turn on the same axis as said flint wheel, a one-way connection between said member and the flint wheel whereby when said member moves in one direction it turns said flint wheel to ignite the wick, a spring tending to move the member in such direction, a pawl carried by said rod engageable with the member to move it in the opposite direction against the action of the spring when the rod is pushed outwardly from the lighting end, said pawl on continued movement moving apart from the member to release the same so that said spring moves the member and turns the flint wheel to ignite the wick, and means to move the rod.

6. In a lighter, a casing having a lighting end and a fuel reservoir therein, a wick extending from within the fuel reservoir through the lighting end, a flint wheel rotatably mounted on the lighting end, means to hold a flint against said wheel, a rod slidably mounted in the casing and extending longitudinally thereof, said rod projecting beyond the lighting end of the casing, a member pivoted to turn on the same axis as said flint wheel, a one-way connection between said member and the flint wheel whereby when said member moves in one direction it turns said flint wheel to ignite the wick, a spring tending to move the member in such direction, a pawl

carried by said rod engageable with the member to move it in the opposite direction against the action of the spring when the rod is pushed outwardly from the lighting end, said pawl on continued movement moving apart from the member to release the same so that said spring moves the member and turns the flint wheel to ignite the wick, a second spring acting on said rod to return the same into the casing, said pawl in such return movement engaging said member and being tilted aside thereby, means engageable with said pawl after it passes the member in such return movement to tilt it to a position to engage said member on the next operating movement of the rod, and means to move the rod.

7. In a lighter, a casing having a lighting end and a fuel reservoir therein, a wick extending from within the fuel reservoir through the lighting end, a flint wheel rotatably mounted on the lighting end, means to hold a flint against said wheel, a rod slidably mounted in the casing and extending longitudinally thereof, said rod projecting beyond the lighting end of the casing, a member pivoted to turn on the same axis as said flint wheel, a one-way connection between said member and the flint wheel whereby when said member moves in one direction it turns said flint wheel to ignite the wick, a spring tending to move the member in such direction, a pawl pivoted on said rod outside said lighting end having a section engageable with the member to move it in the opposite direction against the action of the spring when the rod is pushed outwardly from the lighting end, said section on continued movement of the rod moving apart from the member to release the same so that said spring moves the member and turns the flint wheel to ignite the wick, a second spring acting on said rod to return the same into the casing, said pawl section in such return movement engaging said member and being tilted aside thereby, said pawl having a second section engageable with the lighting end after the first section passes the member in its return movement to tilt the first section to a position to engage said member on the next operating movement of the rod.

8. A lighter comprising an elongated tubular casing containing a fuel reservoir and having a side wall and end walls one of said end walls having projecting from its outer surface only a wick and igniting mechanism, the latter comprising a flint protruding from the casing wall, spaced ears extending from said end wall and a flint wheel rotatably mounted between said ears, a member pivoted to turn on the same axis as said flint wheel, a one-way connection between said member and the flint wheel, whereby when said member moves in one direction it turns said flint wheel to ignite the wick, a spring tending to move the member in such direction, an elongated longitudinally reciprocatable element extending through said casing from one end to the other and having one of its ends projecting through the lighting end wall, a pawl carried upon the outwardly projecting end of said element, said pawl engageable with the member to move it in the opposite direction against the action of the spring when the element is pushed outwardly from the lighting end, said pawl on continued movement moving apart from the member to release the same so that said spring moves the member and turns the flint wheel to ignite the wick, and means at the handle end of the casing to move said elongated element.

9. A lighter comprising an elongated tubular casing containing a fuel reservoir and having a side wall and end walls, one of said end walls comprised by a handle knob for grasping the lighter, the opposite end wall at the lighting end of the device having projecting from its outer surface only a wick and igniting mechanism, the latter comprising a flint protruding from the casing wall, spaced ears extending from said end wall and a flint wheel rotatably mounted between said ears, a sheet metal member bent to a U-shaped configuration having its arms pivotally supported between said ears to turn about the same axis as said flint wheel, a one-way connection between said member and the flint wheel, whereby when said member moves in one direction it turns said flint wheel to ignite the wick, a spring tending to move the member in such direction, an elongated longitudinally reciprocatable element extending through said casing from one end to the other and having one of its ends projecting through the lighting end wall, a pawl pivotally mounted upon the outwardly projecting end of said element, said pawl engageable within a notch in the base portion of the U-shaped member to move said member in the opposite direction against the action of the spring when the element is pushed outwardly from the lighting end, said pawl on continued movement of the element moving apart from the member to release the same so that said spring moves the member and turns the flint wheel to ignite the wick, and means at the handle end of the casing engageable by the thumb when two adjacent fingers grip the knob portion of the lighter to move the rod.

10. A table lighter or the like comprising a base having a well therein, a lighter torch adapted to be contained within the said well during periods when not in use and to have its lighting end inserted therein to quench it after use, said torch comprising an elongated tubular casing containing a fuel reservoir and having a side wall and end walls, one of said end walls comprised by a handle knob for grasping the lighter, the opposite end wall at the lighting end of the device having projecting from its outer surface only a wick and igniting mechanism, the latter comprising a flint protruding from the casing wall, spaced ears extending from said end wall and a flint wheel rotatably mounted between said ears, a member pivoted to turn on the same axis as said flint wheel, a one-way connection between said member and the flint wheel, whereby when said member moves in one direction it turns said flint to ignite the wick, a spring tending to move the member in such direction, an elongated longitudinally reciprocatable element extending through said casing from one end to the other and having one of its ends projecting through the lighting end wall, a pawl carried upon the outwardly projecting end of said element, said pawl engageable with the member to move it in the opposite direction against the action of the spring when the element is pushed outwardly from the lighting end, said pawl on continued movement moving apart from the member to release the same so that said spring moves the member and turns the flint wheel to ignite the wick, and means at the handle end of the casing to move said elongated element.

IRVING FLORMAN.
